JAMES F. KAVANAGH INVENTOR.

BY

O. V. Thiele

ATTORNEY.

UNITED STATES PATENT OFFICE

JAMES F. KAVANAGH, OF CLIFFSIDE, NEW JERSEY, ASSIGNOR TO THE SUPERHEATER COMPANY, OF NEW YORK, N. Y.

HANGER

Application filed December 11, 1928. Serial No. 325,258.

My invention relates to hangers designed to provide a support for a body suspended from a tubular structure, and has particular reference to the suspension of auxiliary equipment from water-tube boilers and like apparatus such as pipe stills, etc.

The invention is particularly suitable for use as a support for a superheater located in the interdeck position in a water-tube boiler and will be described as applied to such an installation, although it is to be understood that it is equally applicable to similar apparatus used for other purposes.

In the accompanying drawings in which I have illustrated preferred forms of apparatus embodying the invention, Fig. 1 is a fragmentary elevation of a standard type of cross-drum water-tube boiler and superheater in which the invention is employed; Fig. 2 is a fragmentary section on an enlarged scale taken along the line of 2—2 of Fig. 1; Figs. 3, 4 and 5 are fragmentary sections showing other devices embodying the invention, and Figs. 5, 6 and 7 are fragmentary elevations of the hangers respectively shown in Figs. 2 and 5.

Referring now to Fig. 1, the conventionally illustrated boiler comprises the usual spaced banks of parallel generating tubes 1 and 2 inclined to the horizontal and which are supplied with water from the steam and water drum 3 by means of nippled headers 4 and 5 and which deliver to the drum 3 through headers 6 and 7 and circulators 8.

The products of combustion from the chamber 9 are caused to pass transversely over the generating tubes by baffles 10 and 11, leaving the boiler through the breeching 12.

The superheater, of known form, is located in the space between the banks of tubes 1 and 2 and comprises transversely disposed inlet and outlet headers 13 and 14 connected by a plurality of superheater elements 15.

The upper bank of generating tubes 2 in a boiler of this character are ordinarily arranged in the manner shown more clearly in Fig. 2, that is, with the several tube rows vertically offset or staggered. As will be apparent from Fig. 1, the location of the super-

heater between the tube banks presents a serious problem with respect to support, particularly as regards the superheater elements 15 which are disposed longitudinally of the boiler. The weight of these elements and of the superheater headers is such that it is impractical to support them from the horizontal row of boiler tubes immediately above them, as such an arrangement would place a greater bending stress upon these tubes than they are capable of withstanding without distortion.

Numerous methods of supporting a superheater have been suggested heretofore, but all of the methods heretofore suggested involve the use of supports independent of the boiler structure which, in addition to adding to the expense of the installation, are for other reasons not entirely satisfactory.

The present invention provides an improved form of support in which the boiler tube structure is used as the supporting medium and in which the load thereon is so distributed that no undue stress is imposed on any of the tubes which carry the supported load.

As illustrated in Fig. 2, the support for the superheater elements comprises one or more transversely placed beams 16 from which depend the rods 17, the latter being provided with heads 18 adapted to be inserted in suitable recesses in the beams 16 to detachably secure the rods to the beams. Rods 17 are provided with extended curved arms 19 adapted to receive the individual loops of the elements 15. So much of the supporting structure as has been so far described is not novel.

According to the present invention, the beams 16 are supported by means of hangers 20 which are in the form of flat metal plates the thickness of which is such that they may be inserted in the relatively narrow space provided between adjacent rows of tubes. As shown in Fig. 2, both of the longitudinal edges of the hangers 20 are formed with spaced arcuate recesses 21 so arranged that when the hanger after insertion between the tube rows is turned through an angle of 90° to the position shown in Fig. 2, each recess 21

will engage a portion of the circumference of one of the boiler tubes. As shown in Fig. 6, the recesses 21 are preferably sloped to conform with the angle of inclination of the boiler tubes.

At the lower end the hangers may be made in any desired form in order to provide a suitable connection between them and the body or bodies which they support. In the form illustrated, the lower end of the hanger is provided with a pair of holes 22 through which transverse supporting pins 23 engaging the beams 16 are passed.

By reference to Fig. 2 it will be quite obvious that the load imposed by the support of beams 16 is, through the medium of the hangers 20, distributed over a relatively large number of tubes. It will further be evident that after having been placed in position, the hangers 20 are securely locked in place but at the same time by the removal of the connecting means they may be readily removed by merely turning them through an angle of 90° and sliding them out through the inter-tube space.

The load on the hangers insures a solid contact at all times between the hanger member and the tubes, which in turn insures an efficient transfer of heat from the hangers to the water-cooled tubes, thereby preventing the overheating and burning of the hangers. Moreover, this construction is particularly advantageous in supporting a structure extending across a relatively wide bank of tubes such as is employed in large power boilers, as the number of hangers employed transversely of the boiler may be as great as is desired, thereby reducing the span between points of support on the beams 16 and consequently reducing the size of the beam section required to resist the bending stress imposed by the closely spaced weight-carrying rods 17.

This feature is particularly desirable in connection with the support of the transversely positioned superheater headers which ordinarily extend through the side walls of the boiler setting and are supported at their ends thereby, but which in the case of wide boilers require additional support intermediate their ends.

In Fig. 3 the hanger 20a functions substantially in the same manner as the hanger 20 but is in a form adapted to be used in connection with banks of tubes 2a in which the tubes are placed in vertically parallel rows rather than in a staggered relation.

Fig. 4 illustrates a form of hanger 20b adapted to be used with the same tube arrangement as is shown in Fig. 2, but in which recesses 21b are provided in only one side of the hanger. This form, however, preferably makes contact with the tube rows on both sides thereof, as in the form shown in Figs. 2 and 3.

In the form shown in Figs. 5 and 7, the

hanger 20c consists of a plate which is bent to form a series of connected hooks and which when in position makes contact with the tube row at but one side of the hanger. Because of the depth of the hooks necessary to secure adequate engagement with the tubes, the hanger cannot be inserted or removed from the tube banks when in the position shown in the figure and must be turned through an angle of 90° for removal, as in the manner necessary for the removal of the other forms of hanger shown. As will be clear from Fig. 6, the width of the hanger is such that when turned through an angle of 90° it can be removed through the space between adjacent tube rows.

In the forms shown in Figs. 2 to 4, the hanger is held against lateral movement by contact with tubes on either side thereof, while in Fig. 5 the hanger is supported by the tubes against lateral motion in one direction only. It will therefore be obvious that this latter form is applicable only in cases where the load thereon is directly vertical and the member or members supported thereby are not free to move transversely.

I claim:

1. The combination with a boiler comprising a plurality of spaced banks of tubes arranged in horizontal rows, the tubes in the banks being parallel and inclined to the horizontal, of a superheater located in the space between said tube banks and a plurality of hangers for supporting said superheater, each of said hangers being in a vertical plane and comprising an element supported by tubes in a plurality of the boiler tube rows above said superheater and having tube engaging surfaces sloped conformably to the inclination of the boiler tubes.

2. The combination with a boiler comprising a tube bank formed by inclined rows of tubes, the tubes in the bank being parallel and inclined to the horizontal, of a superheater suspended from said bank, transverse beams below said bank for supporting the superheater, and a plurality of hangers detachably secured to said beams, each of said hangers lying in a vertical plane and being adapted to be inserted between the adjacent tube rows in said bank and being provided with a plurality of recesses adapted to engage a plurality of tubes in said adjacent tube rows upon rotation of the hanger about its longitudinal axis, said recesses having tube engaging surfaces sloped conformably to the inclination of the boiler tubes.

3. The combination with a bank of tubes comprising a plurality of spaced rows and in which the tubes are parallel and each inclined to the horizontal, of means for supporting the weight of a suspended body comprising a metal hanger lying in a vertical plane and having a plurality of recesses therein and adapted to be inserted between

adjacent tube rows and after insertion to be turned to bring said recesses into engagement with a plurality of said tubes, said recesses having tube engaging surfaces sloped conformably to the inclination of the tubes.

4. The combination with a boiler comprising a bank of tubes arranged in horizontal rows, the tubes in the bank being parallel and inclined to the horizontal, of a plurality of hangers for supporting a body suspended below the bank, each hanger comprising a flat element extending in a vertical plane between two adjacent rows of tubes and engaging a plurality of tubes in each of said two rows, the tube engaging surfaces being in the opposite edges of said flat element and being sloped conformably to the inclination of the tubes, whereby the engaging surfaces are large enough so that relatively few hangers are needed and those engaging only a few tubes each.
